UNITED STATES PATENT OFFICE.

WILLIAM K. HOAGLAND, OF PERU, ILLINOIS, ASSIGNOR OF ONE-HALF TO
THE PERU PLOW AND WHEEL COMPANY, OF SAME PLACE.

CULTIVATOR.

SPECIFICATION forming part of Letters Patent No. 367,913, dated August 9, 1887.

Application filed May 19, 1887. Serial No. 238,789. (No model.)

To all whom it may concern:

Be it known that I, WILLIAM K. HOAGLAND, a citizen of the United States, residing at Peru, in the county of La Salle and State of Illinois, 5 have invented a new and useful Improvement in Cultivators, of which the following is a specification.

My invention relates to straddle-row cultivators, and has the object to improve the construction, adaptation, and operation of parts connecting the spring with the drag-bars.

Referring to the drawings, like letters refer to like parts in all the figures, in which Figure 1 is a perspective view of that part of a 15 straddle-row cultivator in which my improvements are embodied. Fig. 2 is a perspective view of the clevis as improved by me; and Fig. 3 is a perspective view of the "bail," showing its construction.

20 A is the arched axle provided with the wheel arm *a*, sand-cap *b*, and thimble *c*. B are the drag-bars attached to the yoke *d*. C is the clevis attached to the said thimble, and the said yoke pivotally connected to the arms of 25 the clevis; and D is the spring attached to the axle, all of ordinary construction, except as modified to be adapted and used with my improvements, as hereinafter shown.

H is a bail, having the closed end *h* and the 30 arms *m* and *n* provided with perforated ends and loosely pivoted upon the axle A. The said arm *m* is crooked, elbow-like, having means for connecting the spring, as shown, under the axle. The spring is connected to 35 the bail below the axle, that the main force of the spring will be spent against the axle when the plows are at work and have an increasing force upon the plows as they are elevated, as will be understood by inspecting the drawings.

40 *p* is a bar, rearwardly projecting from the lower arm of the clevis, and provided with the downwardly-projecting leg *q*, bearing upon the closed end of the bail, and *l* is a link having one end pivotally connected to the elbow 45 of the arm *m* and the other end connecting to the spring, as shown in the drawings.

In operation, the drag-bars are pivotally

connected to the horizontal part of the axle by the clevis and thimble, the bail loosely pivoted on the axle, with its closed end bearing upon 50 the leg of the clevis and the spring upwardly pulling upon the arm *m*, keeping the said bail snug, and bearing against said leg in all positions of the drag-bars and clevis. When desired to move the clevis to a new position, adjusting 55 the drag-bars, the attachment connecting the clevis to the thimble is loosened and the clevis moved up or down or laterally upon the thimble, and the said attachment again made tight without a liability of loosening the set or any 60 change of the bail or spring-connection, all of which will be understood by inspecting the drawings.

Having thus described my invention, I claim—

1. In a straddle-row cultivator, the bail having the closed end and pivotal upon the axle, in combination with the clevis provided with the rearwardly-projecting bar and downwardly-projecting leg, substantially as and for the 70 purpose shown.

2. In a cultivator, the bail provided with the elbowed or bent arm *m*, and pivotal on the axle, said arm extending first downwardly from the axle and thence rearwardly to the closed 75 end of the bail, as shown, in combination with the spring connected to said arm below the axle, substantially as and for the purpose set forth.

3. In a cultivator, the clevis and the leg *q*, 80 projecting downwardly below the drag-bars, in combination with the bail pivotal upon the axle, and a spring to hold said bail bearing against said leg, substantially as and for the purpose set forth.

4. In a straddle-row cultivator, the combination of the axle A, drag-bars B, yoke *d*, clevis C, bail H, and spring D, all constructed, arranged, and operating substantially as and for the purpose set forth.

WILLIAM K. HOAGLAND.
